UNITED STATES PATENT OFFICE.

EDWIN M. ROSENBLUTH, OF PHILADELPHIA, PENNSYLVANIA.

CARRIAGE-LAMP.

SPECIFICATION forming part of Letters Patent No. 723,488, dated March 24, 1903.

Application filed November 11, 1901. Serial No. 81,815. (No model.)

To all whom it may concern:

Be it known that I, EDWIN M. ROSENBLUTH, of Philadelphia, in the State of Pennsylvania, have invented certain new and useful Improvements in Carriage-Lamps, whereof the following is a specification, reference being had to the accompanying drawings.

My improvements are particularly applicable to lamps which are designed to burn oil while subjected to vibration. If the oil is retained in a free state in communication with the burner in such a lamp, its splashing prevents the uniform operation of the burner, and in order to prevent such disturbance the supply of oil is usually retained in a body of absorbent material. However, such an expedient of course reduces the oil-carrying capacity of the lamp by the bulk of the material in which the oil is suspended.

It is the object of my invention to provide a lamp wherein the maximum oil-carrying capacity is afforded by retaining the oil-supply in a free state, and the complete combustion of the oil is effected uniformly regardless of vibrations of the lamp.

My invention comprises the combination, with a magazine wherein the supply of oil is carried in the free state aside from the burner-wick, of a screen arranged to exclude the splashing oil from the burner-wick and consisting of a capillary medium which is independent of said burner and its wick, but transmits the oil uniformly thereto.

My invention also comprehends improved means to facilitate the complete combustion of the oil by drafting a current of air into and out of the lamp-casing and the various novel features of construction and arrangement hereinafter more definitely specified and claimed.

In the accompanying drawings, Figure 1 is a vertical sectional view of a lamp conveniently embodying my improvements, section being taken on the line 1 1 in Fig. 2, the oil-magazine being in elevation. Fig. 2 shows said lamp sectioned on the line 2 2 in Fig. 1. Fig. 3 is a plan sectional view of the vent-chamber, taken on the line 33 in Figs. 1 and 2. Fig. 4 is a fragmentary plan view of the bottom plate of the vent-chamber. Fig. 5 is a vertical sectional view of the draft-dome

shown in Fig. 1. Fig. 6 is a vertical sectional view of a modified form of draft-dome.

Referring to said figures, A is the flame-casing from whose floor A' projects the air-draft dome B, having an air-outlet b at its top. The bottom of said dome B opens into the air-draft chamber A² within the annular flange A³, depending from said floor A'. Said flange A³ is provided with apertures a² to admit the proper supply of air to the burner C through said draft-chamber A² and dome B, and the products of combustion, &c., escape from the flame-casing A through the chimney A⁴. The casing A is provided with the socket a⁵ in its wall A⁵ to engage a supporting-bracket attached to a vehicle, and said casing A is also provided with the front lens or panel of glass A⁶ and the reflector A⁷, adjoining the rear wall A⁸ and immovably fixed in the casing A, said reflector being apertured at a⁷ to transmit light through the rear signal-jewel a⁸.

The burner C is inclosed by the dome B, with its wick-tube c projecting through the dome-outlet b and the wick-shaft C², provided with the milled head c², extending through the slot b' in the side of said dome. In order that the current of air drafted from the exterior of the lamp through the dome B may be evenly distributed at the dome-outlet b around the burner-wick tube c, I provide the baffle-flange E, which is perforated and serrated, as indicated at e, and conveniently fixed to said tube c.

The oil-magazine D is provided with the central cylindrical partition D', which is separate from the burner C and comprises the screw-thread d', engaged by the thread c' of the burner, which is thus removably secured in fixed relation with the oil-magazine. Said magazine is provided with the screw-thread d², which holds it in removable relation with the casing A by engaging the screw-thread a³ upon the flange A³, depending from the casing-floor A', as shown in Fig. 2. In order that said magazine may be rotated to engage and disengage the casing A while the wick-shaft C² is engaged with the dome B, the latter is mounted to rotate in the casing, its bottom flange B' being rotatably engaged by the flange A⁹, which is fixed in the casing-

floor A'. In the modified form of dome B² (shown in Fig. 6) its bottom flange B³ is recessed, as indicated at b³, and thus rotatably engaged directly with the casing-floor A'.

5 As shown in Fig. 2, the burner-wick C' is separated from the body of free oil F by the capillary fabric screen D⁴, which incloses said wick and transmits comminuted oil thereto through the capillary material D⁵. As the oil is withdrawn by combustion said material D⁵ is automatically recharged with the free oil F through the perforations D⁶ in the cylindrical partition D'. The quantity of oil available in the magazine may be readily ascertained, and the latter may be refilled through the inlet d⁷, provided with the removable screw-plug D⁷.

As shown in Fig. 1, the chimney A⁴ is surrounded by the vent-chamber A¹⁰, which is separated from the chimney, but communicates with the interior of the casing A through the apertures a¹⁰ and with the external atmosphere through the apertures a¹¹, respectively below and above the diaphragm A¹¹, which latter is inclosed by said chamber and provided with the perforations a¹² and air-passage a¹³. Said perforations and air-passage coöperate to transmit a current of air through said chamber A¹⁰, thus cooling the ceiling of the casing A without interfering with the draft of the chimney A⁴, so that complete combustion of the oil-vapor is attained and the polished walls of said casing A are not smoked or tarnished by the products of combustion.

35 I find that the above-described vent structure is rendered more efficient by providing the chimney A⁴ with a cowl A¹⁸, through whose vents a¹⁷ the products of combustion are discharged. The horizontal bottom plate 40 A¹⁴ of said cowl comprises the central port a¹⁴ in registry with the chimney A⁴, but of less diameter than the latter, and air-inlets a¹⁵ exterior to the imperforate side wall of the chimney A⁴ and shielded by the depending 45 side wall A¹⁵ of the cowl. Any exterior current of air encountering the lamp rises through the inlets a¹⁵, is deflected away from the chimney A⁴ by the cowl-walls, as indicated by the arrows on Fig. 1, and is caused 50 to augment the normal draft through the lamp instead of interfering therewith, as is the case if the lamp-chimney is directly opened to the atmosphere through apertures in its side wall. Said cowl may be readily cleaned, 55 as its cover A¹⁶ is separable from the body portion thereof by means of its bayonet-joint connection therewith at a¹⁶.

I do not desire to limit myself to the precise construction which I have shown and described, as it is obvious that various modifications may be made therein without departing from the essential features of my invention.

I claim—

65 1. In a lamp, the combination with a casing inclosing a burner; of a chimney above said burner; a perforated diaphragm surrounding

said chimney; and a vent-chamber inclosing said diaphragm and communicating with the interior of said casing and with the outer atmosphere through apertures respectively located below and above said diaphragm, substantially as set forth.

2. In a lamp, the combination with a casing inclosing a burner; of a chimney above said burner; a perforated diaphragm surrounding said chimney; and a vent-chamber inclosing said diaphragm and communicating with the interior of said casing and with the outer atmosphere, through apertures respectively located below and above said diaphragm; a cowl for said chimney, communicating therewith through a port of less area than the chimney; air-inlets in said cowl exterior to the chimney; and an outlet in the top of said cowl, substantially as set forth.

3. In a lamp, the combination with a burner having a wick; of a casing inclosing said burner; a draft-dome projecting within said casing surrounding said burner; means upon said dome to rotatably engage said casing; an oil-magazine secured beneath said burner; and means to secure said magazine and burner in removable relation with said casing, substantially as set forth.

4. In a lamp, the combination with a burner having a wick; of a casing inclosing said burner; a draft-dome projecting within said casing surrounding said burner; means upon said dome to rotatably engage said casing; an oil-magazine secured beneath said burner; and means upon said magazine to engage said casing, substantially as set forth.

5. In a lamp, the combination with a casing inclosing a burner; of a chimney above said burner; a vent-chamber surrounding said chimney but separate therefrom; a perforated wall separating said vent-chamber from said casing, through which said vent-chamber communicates with the interior of said casing; and a perforated outer wall of said vent-chamber through which it communicates with the outer atmosphere, substantially as set forth.

6. In a lamp, the combination with a casing inclosing a burner; of a chimney comprising an imperforate side wall, above said burner; a vent-chamber surrounding said chimney but separate therefrom; a perforated wall separating said chamber from said casing through which said vent-chamber communicates with the interior of said casing; a perforated outer wall of said vent-chamber through which it communicates with the outer atmosphere; a cowl fixed to said chimney and communicating therewith through a port of less area than said chimney, centrally located in a plate extending horizontally exterior to said chimney; air-inlets to said cowl, opening through said horizontal plate, exterior to the imperforate side wall of said chimney; and a vent in said cowl above said plate, substantially as set forth.

7. In a lamp, the combination with a casing inclosing a burner; of a chimney comprising

an imperforate side wall above said burner; a vent-chamber surrounding said chimney but separate therefrom; a perforated wall separating said vent-chamber from said casing, through which said vent-chamber communicates with the interior of said casing; a perforated outer wall of said vent-chamber through which it communicates with the outer atmosphere; a cowl fixed to said chimney and communicating therewith through a port of less area than said chimney; air-inlets in said cowl exterior to the imperforate side wall of said chimney; a cover for said cowl comprising a vent for the products of combustion; and means to removably secure said cover to said cowl, substantially as set forth.

In testimony whereof I have hereunto signed my name, at Philadelphia, Pennsylvania, this 4th day of November, 1901.

EDWIN M. ROSENBLUTH.
